UNITED STATES PATENT OFFICE.

WILLIAM E. BEATTY, OF BAYSIDE, LONG ISLAND, NEW YORK, ASSIGNOR TO WESTERN ELECTRIC COMPANY, INCORPORATED, OF NEW YORK, N. Y., A CORPORATION OF NEW YORK.

METHOD OF AND MEANS FOR SECRET SIGNALING.

Application filed December 27, 1918. Serial No. 268,467.

To all whom it may concern:

Be it known that I, WILLIAM E. BEATTY, a citizen of the United States, residing at Bayside, Long Island, in the borough of **Queens**, State of New York, have invented certain new and useful Improvements in Methods of and Means for Secret Signaling, of which the following is a full, clear, concise, and exact description.

- 10** This invention relates to a method of and means for secret signaling and more particularly to secret signaling systems in which carrier waves are modulated in accordance with signals.
- 15** An object of the invention is to provide means for transmitting signaling or control impulses which cannot be intercepted by unauthorized parties.

A further object of the invention is to **20** provide a transmission system which may transmit simultaneously successive portions of a message or series of control impulses.

Another feature of the invention is the provision of keyboard operated apparatus **25** by means of which successive portions of the message may be stored up and then simultaneously transmitted.

In the ordinary method of signaling successive elements of the signal or message as, **30** for example, the successive characters or letters used, are transmitted in their proper successive order. According to this invention a plurality of such successive elements are transmitted simultaneously and these **35** elements, simultaneously received at a receiving station, are distinguished from each other and arranged in their proper sequence to produce an intelligible signal or message. In order to make it possible to distinguish **40** the simultaneously transmitted characters it is necessary to transmit each as an energy variation having a characteristic distinctive from that of the others. A system in which each character is transmitted as a modulation of an individual carrier wave would **45** satisfy this requirement. A more satisfactory system, at least from the standpoint of secrecy, is one in which all the simultaneously transmitted characters are transmitted **50** as modulations of the same carrier wave, the modulation for each character, however, being different from that for any of the other simultaneously transmitted characters, as is the case in the "successive modulation" **55** system which will later be described.

Further objects and advantages of the invention will appear from the following detailed description taken in connection with the accompanying drawings, in which Fig. **60** 1 is a diagrammatic view of a radio transmitting station with means for permitting simultaneous transmission of two successive portions of a telegraphic message or series of control impulses; Fig. 2 is a similar view of an arrangement of printing telegraphs **65** and auxiliary keyboard mechanism, whereby a single operator may cause simultaneous transmission of successive elements of a signal; Fig. 3 is a detail view of a single key; and Fig. 4 is a diagrammatic view of a radio **70** receiving system adapted to operate in conjunction with the transmitter of Fig. 1.

Referring to Fig. 1, a high frequency generator 1 is connected by transformer 2 to the **75** input circuit of a thermionic modulator 3. Low frequency signaling current sources 4 and 5 are in circuits with their respective signaling keys 6 and 7. Signaling source 4 is connected inductively to the input circuit of **80** a thermionic modulator 8 and an intermediate carrier frequency source 9 is also connected to this circuit. Signaling source 5 and intermediate carrier frequency source 10, which produces oscillations of a frequency different **85** from the frequency of those produced by source 9, are connected to the input circuit of a thermionic modulator 11. The output circuits of modulators 8 and 11 are each connected to the input circuit of modulator 3, the output circuit of which is connected **90** through a thermionic amplifier 12 to an antenna or transmission conductor 13.

The operation of this system is as follows: **95** An operator is assigned to each of keys 6 and 7, respectively, which may be taken as representative of any transmitting device, such as a simple key or interrupter, or an impulse combination transmitter of a printing telegraph. Sources 9 and 10 produce intermediate carrier frequency oscillations for example, of 20,000 and 30,000 cycles per second, respectively. Low frequency impulses from source 4 are impressed together with the intermediate carrier frequency oscillations from source 9 on modulator 8, the output **100** circuit of which supplies modulated oscillations of the intermediate carrier frequency to the input circuit of modulator 3, to which oscillations of the high carrier frequency are supplied by source 1. If the source 1 pro- **105**

110

duces 100,000 oscillations per second, oscillations of that frequency modulated in accordance with modulated intermediate carrier oscillations from modulators 8 and 11. 5 will be transmitted from the output circuit of modulator 3 through amplifier 12 to the antenna. The antenna oscillations are therefore successively modulated, that is, the high carrier frequency is modulated in accordance 10 with an intermediate carrier frequency, which in turn is modulated by variation currents from source 4.

Suppose, for example, that the word "Eastern" is to be transmitted. The word 15 may be divided into the two groups of letters E, S, E, N and ATR. The operator at key 6 operates that key to transmit the first group and the operator at key 7 operates key 7 to transmit the second group. Consequent- 20 ly the transmission of characters of one group partly or wholly overlaps the transmission of the other group. The energy radiated from antenna 13 is in the form of successively modulated high-frequency carrier waves of one intermediate carrier frequency carrying the impulse variations corresponding to letters E, S, E, N, and high frequency carrier waves modulated by another intermediate carrier frequency car- 25 rying the impulse variations corresponding to the letters "ATR."

Fig. 2 illustrates a transmitting system using three printing telegraph transmitters 14, 15 and 16, each under the control of an 30 auxiliary keyboard apparatus 17, 18, 19. Each printing telegraph transmitter is of the ordinary type in which letters and other characters are transmitted as combinations of electrical impulses. Auxiliary keyboard 17 has a key 20 for each character to be transmitted and corresponds in this respect to the keyboard of transmitter 14. Each key 20 (see Fig. 3) is in the form of a depressible 40 plunger adapted to make electrical contact with a contact member 21 and has a projecting locking or detent lug 31. A cooperating sliding latch 32 is normally held in contact with key 20 by a resilient member 33 acting to force the latch away from fixed frame member 34. A spring 35 or equivalent device holds key 20 in raised position. The depression of key 20 permits latch 32 to engage lug 31 and lock the key in depressed position until released by a slow-acting solenoid coil 36, which upon energization retracts latch 32 against the action of member 33 and permits spring 35 to return key 20 to normal or raised position out of contact 50 with contact member 21. Keys 20 are each connected to a common lead 22 connected to the movable contact of a master key 30, the lower fixed contact 29 of which is connected to a source 23 of electric current. The contact members 21 are insulated from each other and from the frame work of the key-

board. A removable operating board 24 is detachably connected to transmitter 14 and has an electromagnetic tapping device 25 arranged over each key 26 of transmitter 14 in position to strike its corresponding key when 70 energized. Each contact member 21 is connected to a conductor 27 which includes the winding of a corresponding tapping device or tapper 25 and terminates in a common conductor 28 connected to the pole of source 75 23 which is electrically remote from contact 29 of master key 30. Each solenoid 36 has one terminal connected to conductor 22 and the other terminal connected to conductor 28. The circuits of auxiliary keyboards 80 18 and 19 and their corresponding transmitters 15 and 16 are in every respect like those just described.

Suppose that the syllable "cab" is to be transmitted, the operator depresses key "C" 85 on auxiliary keyboard 17, and keys "A" and "B" on keyboards 18 and 19 respectively. Each depressed key locks down. For each of the depressed keys an energizing circuit is now prepared as follows: 90 lower contact 29 of key 30, source 23, conductor 28, tapper winding 25, contact 21, depressed key 20, conductor 22 to key 30. Each solenoid coil 36 is also in a circuit with source 23 which is open only at master key 95 30. Consequently, the closure of key 30 actuates tappers 25 simultaneously to set up corresponding telegraphic combinations and also actuates slow-acting solenoids 36 to withdraw all the latches 32 and release 100 all depressed keys shortly after the combinations are set up. Since each transmitter 14, 15, 16 is assigned one of three successive portions of the message, these three portions are transmitted simultaneously. The three transmitters 14, 15, 16 are each arranged in a transmission system such as described in connection with Fig. 1, each printing telegraph being substituted for one of the low frequency signaling sources and its key. It will of course be understood that 105 although two signal transmitters are indicated in Fig. 1 and three in Fig. 2, any number may be used, the circuit arrangements for additional ones corresponding in every way to those shown, with an individual intermediate carrier frequency source for each. 110

Fig. 4 illustrates a receiving system comprising an antenna or receiving conductor 37 and a thermionic detector 38 connected thereto, having an output circuit inductively connected to circuit 39, in which a number of tuned selecting circuits 40 are arranged in series. Each selecting circuit is tuned for 115 a particular intermediate carrier frequency and serves as an input circuit for a thermionic detector 41 individual thereto, the detector having an output circuit arranged to supply detected impulses or variation currents to a receiving printing telegraph de- 120 125 130

vice 42. In the system of Fig. 4, two printing devices 42 are illustrated with a tape or traveling record-element 43 fed either by independent mechanism or by a device controlled by the printing operation in the manner well known in the art. Where each of the printing telegraphs operates to step the tape-feeding mechanism by means of a pawl and ratchet mechanism, the operation of any one of the receivers 42 will serve to move the tape.

Assume that the transmitting apparatus illustrated in Fig. 1 is being used to transmit the word "Eastern" to the receiving apparatus of Fig. 4. Successively modulated waves carrying simultaneously the character impulses of letter "E" and "A" are received by antenna 37. Successively modulated oscillations are accordingly supplied to detector 38 and singly modulated current components of the two intermediate carrier frequencies appear simultaneously in its output circuit. Correspondingly modulated currents of these two frequencies are supplied to circuit 39. One tuned input circuit 40 selects the modulated intermediate carrier frequency oscillations of the frequency produced in the output circuit of modulator 8, and the other circuit 40 is tuned to select the currents of the frequency set up in the output circuit of modulator 11. Detectors 41 will accordingly supply to their respective printers 42, impulses corresponding to those supplied by the circuits of sources 4 and 5, and the printers print letters "E" and "A" respectively on the traveling tape, one printer printing its character on a portion of the tape slightly in advance of the portion upon which the other printer operates. The tape is fed forward after each printing operation a distance sufficient to accommodate as many successive characters as there are printers. Obviously each printing telegraph may operate to print characters upon an individual tape. The tapes may then be assembled side by side to read the message.

The printing telegraph receivers 42 might equally well be replaced by Morse recorders in the case of Morse signal transmission, or if control impulses are being sent out to select or control circuits, each receiver may control a selector of any suitable sequence selecting mechanism, the joint action of the selectors serving to select the desired element or circuit.

The thermionic modulators, detectors and amplifiers have all been illustrated as of the ordinary highly evacuated thermionic type including a heated cathode, an anode and an impedance controlling element. Each may, however, be replaced by equivalent functioning apparatus of any desired form. It should also be understood that dynamo electric alternators or vacuum tube oscillators or

any other type of alternating current sources of the proper frequency may be used. As in the ordinary case, high frequency wire transmission may be employed instead of radio transmission.

This system is secret to the extent that successively modulated waves require for their detection either a local source of high frequency oscillations of proper frequency, or a tandem arrangement of detectors and further that anyone attempting to pick up the message would succeed in getting only the portion carried on one intermediate carrier frequency. Since the number of intermediate carrier frequencies may be made large, the task of intercepting the entire message may be made very difficult.

Although the invention has been illustrated and described in connection with certain specific forms of radio transmission circuits, it is to be understood that it is not limited to any of the specific systems or features involved in these systems, but only by the scope of the appended claims.

What is claimed is:

1. The method of signal transmission which comprises producing a plurality of different waves modifying each in accordance with an individual one of a series of sequentially occurring elements of a signal and simultaneously modifying a common carrier wave by all of said plurality of modified waves.

2. The method of signal transmission which comprises transmitting sequentially groups of elements of a signal, each group comprising a plurality of successive elements of the signal, the transmission of all of the elements of any one group being concurrent.

3. The method which comprises producing energy representing a plurality of successive elements of the same signal and modulating a common carrier wave simultaneously in accordance with the energy representing all of said plurality of elements.

4. The method of impulse transmission which comprises transmitting a carrier wave having a plurality of different successive modulations representing successive elements of a series of impulses.

5. The method of impulse transmission which comprises transmitting a carrier wave having a plurality of different successive modulations, receiving said carrier wave and producing an intelligible record thereby.

6. The method of signal transmission comprising successively setting up different elements of a signal and simultaneously transmitting said different elements.

7. The method of storage transmission which comprises storing successively a plurality of elements of a message and then transmitting energy simultaneously representing all of said elements.

8. The method of impulse transmission

which comprises storing successive impulses in successive time order as displacements of character mechanism, and simultaneously transmitting impulses as a result of said displacements.

9. The method of transmission which comprises modifying a plurality of different frequency carrier waves each in accordance with an individual element of a sequence of 10 characters, and simultaneously transmitting the energy of said carrier waves.

10. A transmission system comprising means for simultaneously transmitting on different frequency carrier waves, a plurality of predetermined portions of a series 15 of impulses.

11. A transmission system comprising means for successively storing up elements of a message, and means for simultaneously transmitting energy representing said elements.

12. A signal transmission system comprising a signal transmitter, means for successively setting up in said transmitter different elements of the signal and means for simultaneously transmitting said different elements over a transmission circuit.

13. A transmitting arrangement comprising a plurality of character members, means 30 for operating said members in succession, and means for causing said plurality of character members, after each has been op-

erated, to simultaneously transmit impulses corresponding to their respective characters.

14. A transmitting device, an impulse transmitter having a plurality of character elements, means for operating said elements in a time succession, a transmitting circuit under the control of each of said character elements, and means to cause a plurality of 40 said character elements, after all have been operated, to act simultaneously upon said transmitting circuit.

15. A storage transmission system, comprising means for successively storing up a 45 plurality of elements of a message and means for transmitting energy simultaneously representing all of said elements.

16. In combination, a printing telegraph transmitter having a plurality of keys, 50 means associated with each of said keys to transmit energy having characteristics individual to that key, a controlling device having a number of keys each of which corresponds to a key of said transmitter, and 55 means whereby successive operation of the keys of said controlling device causes simultaneous operation of the corresponding keys of said transmitter.

In witness whereof, I hereunto subscribe 60 my name this 20th day of December, A. D., 1918.

WILLIAM E. BEATTY.
